UNITED STATES PATENT OFFICE.

MELCHOR CENTENO V., OF CARACAS, VENEZUELA.

PHOTO-ELECTRIC CELL.

Application filed November 6, 1926. Serial No. 146,794.

This invention relates to a photo-electric cell. Such cells are commonly based upon the property of a film of selenium varying its resistance under varying degrees of illumination by which such changes are rendered evident in a magnetically controlled electric circuit. My invention is based on a very different form of electric influence on a photo-electric medium. It is based on the principle discovered about 60 years ago by Bunsen and afterwards elaborated by other scientists, which demonstrated that nascent chlorine and hydrogen were influenced by light emissions to a varying degree depending upon its luminosity, in sunshine producing a violent explosion by the chemical reaction, and in shadow proceeding more slowly with a less explosive tendency, but in all cases effecting a resultant chemical combination forming hydrochloric acid with a resultant enormous reduction in molecular mass. So far as I am aware this principle has had no practical application and my photo-electric cell accomplishes a practical result of the chemical reaction as an effective photo-electric transformation into electric energy.

In carrying out the invention I provide a generator of hydrogen and chlorine and store it in a small circulation circuit including means for keeping it in constant circulation from the supply end and back through a waste receptacle. In the path I interpose a closed box acid-proof on the interior, the front of which has means for admitting variable light densities and the back of which has a microphone across which runs the circuit of chlorine and hydrogen. To accentuate the reaction I interpose in the gaseous circuit in the plane of the projected light a strip of porous material impregnated with platinum black, or a film of the same may be applied to the microphone diaphragm. The microphone includes an electric generator and the light opening to the box is preferably provided with a rotative shutter so that the light through the box is rapidly intermittent. Thus the various light impulses admitted to the box create a series

of explosions on the diaphragm of the microphone of varying degree in proportion to the strength of light passing through the shutter, and this is accentuated by the catalytic effect of the platinum black on the moving gas. The gaseous medium being kept in motion provides fresh molecules continuously.

The invention, therefore, consists of a photo-electric cell in an inclosed chamber containing a moving stream of hydrogen and chlorine, means for intermitting light to the chamber, and a microphone in the chamber in the path of the light. It comprises other and more specific features, the novelty of which will be hereinafter fully set forth and will be definitely indicated in the appended claims.

In the accompanying drawings illustrating the invention:

Figure 1 is a sectional view of a microphone.

Figure 2 is a face view of a modified microphone.

Figure 3 is a sectional view of a microphone and light interrupter.

Figures 4 and 5 are detail views of a microphone with light opening.

Figures 6, 7, 8, 9 and 10 are details of the combined box and microphone parts.

Figure 11 represents a complete circuit of the gaseous medium.

Figure 12 is a sectional detail with the lens in the light opening.

Figure 13 shows one manner of applying the catalytic material.

Figure 14 illustrates a rapid shutter.

Figure 15 is a plan view of Figure 14.

Referring now in particular to the drawings, 1 represents a closed box with a light opening 2 in its cover. The box is provided with a threaded lid 4 with a diaphragm 5, preferably of thin treated carbon commonly employed for microphone use, through which are lead pipes 6, 7 to admit gaseous chlorine and hydrogen to the box. Terminals 8, 9 are provided at one end of the diaphragm and the other at a central point. I preferably provide soft rubber washers 9, 10 as in

the form shown in Figure 3 to give a soft elastic seat for the carbon disk. The form shown in Figure 3 also produces a better microphonic contact by employing a thicker disk of carbon 11 in the cap, which bears against four hard carbon balls 12. In front of the light opening 2 is placed a rotative disk 13 perforated with a plurality of circumferential openings 14 to produce an intermittent beam of light through the glazed or lens opening 2. The box, instead of a plain glazed opening, may carry a double convex lens 15 to effect an image field on the microphone diaphragm, and across this focal intersection may lie a perforated porous disk 16 impregnated with platinum black. This acts as a catalyst, promoting the chemical union of hydrogen and chlorine and assists the reaction.

20 The combined camera and microphone are mounted in the circuit of the gaseous medium, as shown in Figure 11, so that the pipe circuit 17 including a pump 18, a source of gaseous medium 19 and a bottle 20 containing any liquid waste due to the chemical reaction, form a complete circuit in which the pump maintains a continuous flow of gases. The circuit preferably contains control valves 21 and 22 for regulating the feed.

30 In front of the lens is the rotative perforated disk 13 provided with a circumferential series of perforations which may be driven, see Figure 14, by an electric motor 23 derived from a commercial source of voltage and belted to the rotative disk 13 by a belt 24. It will thus be seen that I have provided means for causing the combined gases, hydrogen and chlorine, to react chemically under the influence of an intermittent beam of light. The variable explosive effects due to the intermittent rays produce explosions at the face of the microphone diaphragm, which vary the contact between the microphonic contacts and alter its electric resistance so that a circuit and battery included therein would give a varying strength of current proportional to the degree of illumination of rays impinging the path of the gaseous medium, and can be rendered sensible as a sound of varying intensity in accordance with the degree of illumination; and if such illumination resulted from the shade and shadow of a camera field such as produced by a lens 15 or other means, it would produce 50 a musical rhythm according to the rapidity of the rotative disk 13 and number of its openings, which would produce pitch in a tone, and the varying degree of illumination would produce quality or timbre so as to 55 give a distinctive musical note. A considerable number of similar photo-electric cells might be employed to produce simultaneously or in sequence such rhythmic variations of electric current. One application 60 of such a system might be applied to photo-

graphing a scene, parts of the image area being exposed to separate cells either simultaneously or in sequence. Another application would be in moving picture transmission, in which any form of suitable receiver 70 responsive to the different cells might be used and transmitted to any approved known type of receiving mechanism. The several cells might by their shutter mechanisms have varying pitches or wave lengths which 75 the receivers might differentiate and re-compose.

I would remark that I have referred to my cell as acting in connection with a perforated rotative disk as one type of interrupting the light to effect conversion into electric impulses, but that was merely by way of example, as there are many known ways of using varying types of shutters many forms of which have been used in the 85 moving picture art and other forms of converting systems, and I would have it understood that I may employ any approved type to utilize my sensitive photo-electric cell.

I have herein described the best form of 90 mechanism I have hitherto devised to carry out my photo-electric improvements, but I desire that it be understood that I am not limited to the specific means recited, but that modifications of the apparatus and alternative means may be employed, without departing from the scope of my invention.

Having thus described my invention, what I claim as new and desire to secure by Letters Patent is:

1. A photo-electric cell comprising a closed acid-proof chamber with a transparent opening therein, a microphone in the path of transmitted light, a current of hydrogen and chlorine passed through the 105 chamber, and means for admitting intermittent light rays through the opening.

2. A photo-electric cell comprising a closed acid-proof chamber with a transparent opening therein, a microphone in the path of transmitted light, a current of hydrogen and chlorine passed through the 110 chamber, and means for admitting variable light rays through the opening.

3. A photo-electric cell comprising a closed chamber with a transparent light opening therein, a microphone in the path of the light rays, a moving stream of hydrogen and chlorine adjacent the microphone, and a shutter admitting light to the chamber.

4. A photo-electric cell comprising a camera, a microphone therein in the focus of the camera, a moving stream of hydrogen and chlorine adjacent to the microphone, means for admitting variable light to the camera, and an electric generator in the microphone circuit.

5. A photo-electric cell comprising a closed acid-proof chamber with a transpar-

ent opening therein, a microphone in the path of the transmitted light, a shutter controlling admission of light, a current of hydrogen and chlorine adjacent to the microphone, and a catalytic agent adjacent the image to promote chemical reaction.

6. A photo-electric cell comprising a

closed acid-proof chamber, means for introducing variable light therein, a microphone in the path of the light, a current of hydrogen and chlorine through the chamber, and a pump producing a circulation of the gases. ¹⁰

In testimony whereof I affix my signature.

MELCHOR CENTENO V.
